The ornamental design for guardian angel doll, as shown.

DESCRIPTION

FIG. 1 is a front elevational view of a guardian angel doll showing my new design;

FIG. 2 is a rear elevational view thereof, and
FIG. 3 is a side elevational view of the doll.

The side opposite to that shown in FIG. 3 is an exact mirror image of the side shown.

FIG. 1
